PACKAGING FORM FOR A COLLAR OR THE LIKE

Myron S. Strasser, Jr., 512 Bradford St., Albany, N.Y.
12206, and Samuel A. Strasser, 124 Salisbury Road,
Delmar, N.Y. 12054

Filed Jan. 9, 1967, Ser. No. 5,342

Term of patent 14 years

(Cl. D9—294)

FIG. 2.

FIG. 1.

FIG. 3.

FIG. 4.

FIG. 1 is a perspective view of a packaging form for a collar or the like embodying our new design;

FIG. 2 is an elevational view;

FIG. 3 is a front elevation of the packaging form as seen with a shirt collar in dot and dash lines; and

FIG. 4 is a sectional view taken on the line 4—4 of FIG. 3.

The broken line showing of a portion of a shirt in FIG. 3 is for illustrative purposes only.

We claim:

The ornamental design for a packaging form for a collar or the like, substantially as shown and described.
